UNITED STATES PATENT OFFICE.

HENRY McMASTER, OF HIGHLAND PARK, MICHIGAN, ASSIGNOR OF ONE-HALF TO
JASPER W. DAVIS, OF DETROIT, MICHIGAN.

INSOLE.

1,342,967.

Specification of Letters Patent. Patented June 8, 1920.

Application filed February 7, 1919. Serial No. 275,535.

To all whom it may concern:

Be it known that I, HENRY McMASTER, a citizen of the United States of America, residing at Highland Park, in the county of Wayne and State of Michigan, have invented 5 certain new and useful Improvements in Insoles, of which the following is a specification, reference being had therein to the accompanying drawings.

- 10 In uniting the uppers to the soles of shoes, there is usually formed a ridge within the shoe along the meeting angle of the upper and sole, particularly in welt work, and in practically all constructions after consider-
15 able wear, this edge portion of the sole is considerably higher than the central portion. To give a smooth inner surface, a sock lining or insole is usually provided, but after a time the margin of this insole will 20 curl upwardly and inwardly due to the raised portion of the sole and to the damp-
ness of the under side of this margin caused by lack of ventilation. This inwardly curling edge often causes great discomfort to
25 the wearer.

Separate, detachable insoles as commonly constructed, will, in a like manner curl upwardly and inwardly along their margins, due to the same causes, and it is the object 30 of this invention to provide an insole or sock lining which is so constructed as to prevent this curling of its edge portion and will always present a smooth upper surface within the shoe across the entire width of the sole.
35 With these and other ends in view the invention consists in the matters hereinafter described and more particularly pointed out in the appended claim reference being had to the accompanying drawing, in which—

- 40 Figure 1 is an inverted plan view of an insole or sock lining embodying the invention;

Fig. 2 is a transverse section of the same substantially on the line $x-x$ of Fig. 1;

- 45 Fig. 3 is a perspective view of the same with the upper ply turned back to more clearly show the construction;

Fig. 4 is an enlarged transverse section of a shoe sole with the upper secured in place 50 thereon in the usual manner, and a detachable insole embodying the invention in place upon the shoe insole within the shoe;

- Fig. 5 is a perspective view of a modified construction of insole showing the bottom 55 facing of the insole detached and turned

back to disclose a padding interposed between this facing and the upper portion or body of the insole; and

Fig. 6 is a transverse section of a shoe with the modified construction of insole 60 shown in Fig. 5 applied thereto.

The sock lining or insole embodying this invention consists of a sheet or body of leather or other suitable material which is cut so that its margin will conform closely 65 to the shape of the sole of the shoe within the upper thereof, with the edge of the insole lying close to the wall of the upper along the entire length thereof. A marginal portion of this body A is cut away as at 1 70 for a distance inwardly from the edge of the body at the lower or underside thereof, or the body may be formed of two or more layers of material 2 and 3 as illustrated in Fig. 2, the lower ply 3 having the same out- 75 line as the upper ply 2 but of less width so that the edge channel or groove 1 is pro-
vided in the lower face of the body along its edge, leaving the thin edge portion 4 of the layer 2 to overlie the welt 5 and attached 80 and inturned edge of the upper 6 or other ridge or projection which may be formed by the attachment of the upper to the sole of the shoe. The ply 3 forms a thickened central portion for the body so as to hold the 85
ply 2 level with its thin edge portions 4 ad-
jacent the wall of the upper, the channel or groove 1 forming, when the insole is in place within the shoe, an air channel 7 all along the margin of the insole adjacent the upper. 90 The pressure in use, comes upon the central portion of the insole and because of the thin lip or margin 4 with the open channel be-
neath it, there is no tendency of the lip 4 to curl upwardly and inwardly, and this curl- 95 ing is also prevented by the channel 7 which forms an air passage providing ventilation to keep the underside of this thin lip 4 from becoming more moist than the upper surface thereof.

As shown in Figs. 5 and 6, the central portion of the body of the insole may be increased in thickness by providing a pad 8 therein of any suitable material such as felt, this pad being interposed between a com- 105 paratively thick upper ply 9 and a thin lower ply 10 or surfacing which is of lesser width than the ply 9 to provide a marginal groove 11 along the underside of the insole. This marginal groove may extend only 110

along the edge of the toe portion of the insole, as shown, or it may extend along the entire margin thereof.

A sock lining or insole constructed as described, may be incorporated in the shoe itself, being secured to the sole in any desired manner or it may be used as a separate detachable insole which may be applied to any shoe with the thick central portion thereof resting upon the insole 12 of the shoe, the salient features of the device being a body having a central portion resting upon the shoe sole or sock lining with a thin margin conforming to the shape of the shoe and lying close to the upper, the body and margin presenting a continuous smooth upper surface extending across the entire width of the shoe, with an open ventilating channel beneath this thin lip or margin along the wall of the upper.

Obviously, changes may be made in the construction of the device without departing from the spirit of the invention and I do

not therefore wish to limit myself to the specific construction and arrangement shown. 25

What I claim is:

A separate detachable inner sole comprising a body formed of upper and lower thicknesses of material with a padding interposed between said thicknesses, the lower thickness being of less width and length than the upper thickness to provide a margin of a single thickness and the area of the padding being less than the area of the lower thickness of material to provide a cushion at the central portion of the body only, said padding having a thin margin and said upper and lower thicknesses of material being secured together along their contacting marginal portions outside of said padding. 30 35 40

In testimony whereof I affix my signature in the presence of two witnesses.

HENRY McMASTER.
